UNITED STATES PATENT OFFICE.

WILLIAM H. BECKER, OF CANDO, NORTH DAKOTA.

DESIGN FOR A BADGE.

SPECIFICATION forming part of Design No. 29,483, dated October 18, 1898.

Application filed July 8, 1898. Serial No. 686,458. Term of patent 7 years.

To all whom it may concern:

Be it known that I, WILLIAM H. BECKER, a citizen of the United States, residing at Cando, in the county of Towner, State of North Dakota, have invented and produced a new and original Design for a Badge, of which the following is a specification, reference being had to the accompanying drawing, wherein the single view represents in plan a badge showing my new design.

As shown in said drawing, the essential features of the design are representations of the Goddess of Liberty and the Queen of Great Britain facing each other, the flags of said two respective countries crossed and bound together, and the American eagle and the British lion facing each other across a space occupied by a cut representing a crossed gun and sword. The said several figures above noted occupy prominent positions on a suitable field, which, as shown, is a body of flexible material. This flexible body is mounted to depend from a suitable head-plate adapted to secure the badge to the wearing-apparel

or elsewhere in its proper working position. 25 The strip is also provided with a depending body of fringe at its lower end. The figures are shown arranged in the following order on the flexible strip, to wit: the Goddess of Liberty and the Queen of Great Britain near the 30 top of the strip, or directly below the head-plate, the two flags next in order directly below said two personages, and the eagle and the lion, together with the crossed sword and gun, at the foot of the strip or directly above 35 the depending fringe.

Having described my invention, what I claim as new, and desire to secure by Letters Patent of the United States, is—

The design for a badge, substantially as 40 herein shown and described.

In testimony whereof I affix my signature in presence of two witnesses.

WILLIAM H. BECKER.
